MULTIPLE BAND BLADE SLICING MACHINE

William Walter Hartman, Los Angeles, Calif.

Application May 23, 1940, Serial No. 336,842

6 Claims. (Cl. 146—88)

This invention relates generally to machines for slicing articles, such as loaves of bread, and more particularly to slicing machines of the multiple endless band blade type.

It has for some time been the considered weight of opinion among those skilled in the art to which the present invention appertains, that proper tensioning of the blades of a multiple band blade machine necessitates individual means for tensioning each blade. This practice has been followed partly from the fact that individual band blades as heretofore manufactured have varied in length to a substantial degree, and partly, perhaps, by the belief that the blades were being taxed beyond their elastic limits under service conditions, and that blade lengthening over a period of time was a factor necessary to be compensated. More recently, however, it has been ascertained that with due care in manufacture, blades of very uniform length can be produced, and careful investigation has also revealed that the blades are not actually or necessarily stretched beyond their elastic limits in service. Accordingly, by exercising a high degree of care to see that all the blades to be used on a given machine do not depart from a predetermined length by more than a given tolerance, it is possible to tension all the blades at once by exerting tensioning pressure on a single drum about which all the blades run. A safe tolerance is, for instance not more than .001" for each foot of blade length.

A primary object of the invention accordingly may be stated to be to provide an improved multiple band blade slicing machine in which all of the blades are tensioned by novel and improved means for exerting tensioning pressure on a single drum about or against which all the blades run.

A further object of the invention is the provision of novel and improved means for exerting blade tensioning pressure on a blade supporting drum of a band blade slicing machine, in conjunction with novel and improved means for facilitating the mounting of the blades on the blade supporting drums of the machine.

The present invention is here illustrated in the form of a band blade slicing machine of the two-drum, figure-8 type, and while certain features of the invention have to do particularly with the figure-8 type of machine, and are particularly applicable to that type of machine, in broader aspects the invention is not to be considered as restricted to figure-8 machines, and the claims appended to the present specification are accord-

ingly not to be considered as limited to the figure 8 type of machine unless expressly so stated.

In accordance with the present invention, a drum about or against which all of the blades of the machine run is provided at each of its ends with mounting means including a spring element which urges the drum to move in a direction to tension the blades. Means are provided for stressing these springs to exert a predetermined pressure on this blade tensioning drum, and these spring-stressing means are always set up to a fixed limiting position at which an accurately predetermined pressure is exerted, but beyond which further travel is impossible by reason of the provision of certain engaging stop elements, so that this predetermined pressure cannot be exceeded. It is important that the pressure so exerted on the drum be limited to a proper predetermined working value, both from the standpoint of avoiding over-stressing of the blades, and from the standpoint of avoiding stressing the bearings for the several drum shafts beyond the point for which they were designed. Arrangements are further provided for withdrawing the spring-stressing means to relax the pressure exerted by the springs, thereby bringing about sufficient retraction of the blade tensioning drum to permit installing or removing blades. When the means for stressing the springs are then re-set, the pressure exerted on the drum goes back precisely to, and cannot exceed, the value accurately predetermined in the factory, and there is positive assurance that the blades will not be overstressed, and the bearings for the drum shafts will not be over-taxed.

The present application is a continuation, in part, of my copending prior application entitled Multiple band blade slicing machine, Ser. No. 249,047, filed January 3, 1939, and which became 40 Patent No. 2,205,527 on June 25, 1940, the present application disclosing and claiming certain subject matter of invention disclosed but not claimed in the aforementioned parent application.

Various additional objects and features of the 45 invention will appear and be fully described in the course of the following detailed description of a present illustrative embodiment thereof, reference for this purpose being directed to the accompanying drawings, in which:

50 Fig. 1 is a side elevation of a slicing machine in accordance with the present invention;

Fig. 2 is a section taken on lines 2—2 of Figs. 1 and 3;

55 Fig. 3 is a section taken as indicated by line 3—3 of Fig. 2;

Fig. 4 is a section taken as indicated by line 4—4 of Fig. 2;

Fig. 5 is a section taken on line 5—5 of Fig. 4;

Fig. 6 is a section taken on line 6—6 of Fig. 2;

Fig. 7 is a detail of a spring assembly, taken 5 from Fig. 6;

Fig. 8 is a section taken on line 8—8 of Fig. 2;

Fig. 9 is a section taken on line 9—9 of Fig. 3; and

Fig. 10 is a section taken on line 10—10 of Fig. 10 1, showing certain frame features but omitting the drive gear.

While the present invention may be regarded as particularly applicable and adaptable to what is commonly referred to as the "figure-8" type of slicing machine, and is here illustrated as incorporated in such a machine, it is nevertheless to be understood that various features of the invention are applicable also to other types of band blade machines, and no limitation to any particular type of machine is therefore to be inferred, except where expressly so indicated.

With this understanding, reference is now directed to the drawings, in which the illustrative slicing machine is designated generally by numeral 10. The general frame structure of the machine includes a base 11, upon which is mounted a vertically elongated rectangular frame or housing structure 12 surmounted by a top 13. Mounted on base 11 and extending upwardly to top 13, at one side of the machine, is a channel member 14 which constitutes a part of the stationary frame, and on which certain operative parts of the machine are mounted, as later to be described. In the present instance, this channel member is disposed at somewhat of an angle with reference to vertical, such as indicated in Fig. 1, which results in a certain convenient disposition of the various members of the machine, and also in a desirable downward inclination for the path of the loaves as they are passed through the cutting blades. It will be understood, however, that the particular disposition of the channel member 14, and of the parts mounted thereon, with reference to vertical, is open to considerable modification, and that no limitation is to be implied from the particular disposition here illustrated. At the four corners of the rectangular frame structure are vertical frame members 15, of angle cross-section, extending 50 from base 11 to top 13, while opposite sides of the frame structure are closed by swinging doors 16 and 17 hinged to angle members 15 at 16a and 17a, respectively. Half-round plates 19 are welded to the flanges of angle members 15, as indicated in Fig. 10, to give a finished appearance to the housing.

A plurality of endless band blades 20 are looped over upper and lower band blade supporting drums 21 and 22, respectively, which preferably and as here illustrated are of the same diameter and have their axes substantially parallel. Each blade goes on drums 21 and 22 in figure-8 form, with the upper blade loop being passed over upper drum 21, the blade being then twisted 65 through a half turn, and the lower blade loop then being passed over lower drum 22. This threading arrangement brings the cutting edges 20a of the central portions of both courses of each band blade to a position where they cross one another and where they are directed toward the front end of the machine, from which direction the loaves or other articles to be sliced are fed against the blades.

Lower drum 22 is revolvably mounted on a non-rotatable shaft 23, one end of which is tightly fitted within a mounting 24 secured to the lower end portion of the aforementioned channel member 14, in the manner clearly illustrated in Fig. 2. Drum 22 comprises a cylindrical shell 25 mounted on drum ends 26 and 27, which are mounted for rotation, as by means of bearings 27a, on the aforementioned fixed shaft 23. The entire weight of the drum may thus be supported by the one fixed end of shaft 23. A removable support is provided for the other end of shaft 23. Thus, as here typically shown, said end of the shaft has a conical socket 28 adapted to be engaged by the pointed end 29 of a supporting screw 30 screwthreadedly mounted in a mounting block 31 secured to base 11. The inner side of mounting block 31 is spaced somewhat from the outer end of drum 22, so as to give a clearance space, when the screw 30 is retracted, through which the blades may be passed in the operation of looping them over the lower drum during assembly.

The end of drum 22 adjacent channel member 23 is formed with a pair of peripheral V-grooves 33 for driving V-belts 34, which are driven by pulley 35, powered through suitable reduction gearing, not shown, from the shaft of an electric motor 36 mounted on base 11.

Upper drum 21 comprises a cylindrical shell 40 mounted on a pair of drum ends 41, which are revolvably mounted through bearings 42 on a non-rotatable shaft 43. The end of shaft 43 adjacent channel member 14 is tightly mounted within a hub 44 formed at the upper end of a slide member 45, the edge portions of which are received and guided within a way provided by jib plates 46 secured to channel member 14 as by means of screws 47 (see Figs. 4 and 5). The member 45 comprises the supporting member for the corresponding end of drum shaft 43, and is in turn supported through spring means as presently to be described.

The way defined by the jib plates 46 extends in the direction of the plane defined by the axes of drums 21 and 22, and it will be apparent that movement of member 45 upwardly or downwardly in said way tensions or de-tensions the blades as the case may be.

Member 45 has at the bottom a wall or abutment 50, which engages and is supported by the upper end of a compression spring 51, the lower end of which seats on a spring supporting element 52, here shown in the form of a centrally perforated disk. This spring supporting element 52 rests on the upper end of a lead screw 53, which coacts with and works through an internally screwthreaded bevel gear 55. The lower end of the latter rests through thrust bearing 56 on a bracket 57 mounted on channel member 14. Thus, the downward pressure sustained by drum supporting member 45 is transferred via spring 51, spring supporting element 52, lead screw 53 and bevel gear 55 to bracket 57 mounted on channel member 14 which is a part of the fixed frame. Lead screw 53 is prevented from turning by means of a key, here in the form of a screw 58, engaging in a longitudinal spline-way 59, screw 58 being mounted in a bracket member 60 secured to channel member 14. Bevel gear 55 is turned by means of a meshing bevel gear 62 on the inner end of a shaft 63 turning in a bearing 64 mounted on channel member 14 (see Fig. 2), the other end of said shaft 63 having thereon a hexagonal head 65 adapted to be engaged and

rotated by means of a crank 66 or any other suitable means.

Rotation of gears 62 and 55 by means of crank 66 causes lead screw 53 to be elevated or lowered. Elevation of lead screw 53 is limited by means of a stop nut 70 secured as by pin 70a on the lower end of the lead screw and adapted to engage the lower side of bracket 57 when the lead screw reaches a predetermined elevation. A tension rod 71 having a head 72 on its upper end extends downwardly through an aperture 73 in wall 50, longitudinally through spring 51, through element 52, and is screwthreaded into the upper end of lead screw 53, as clearly illustrated in Fig. 4. The purpose of this tension member will be described at a later point in the specification.

The opposite end of upper drum shaft 43 is supported, when the machine is in operation, by means of a mounting preferably in the form of a pivoted hanger 76, here shown as pivotally mounted on a pivot pin 77 carried by a mounting member 78 secured to frame top 13 as by means of screw 79 (Figs. 2 and 6).

The hanger, in the particular form here illustrated, comprises a tubular body 80, having at its upper end an upper head 81 mounted on pivot pin 77, as illustrated in Fig. 6. Tubular body 80 has just below head 81 an aperture 82 adapted to receive, with clearance, the reduced and tapered end portion 83 of shaft 43, the flattened underside 84 of the latter bearing downwardly on a shaft supporting element or disk 85 movable longitudinally inside tubular body 80. Disk 85 rests on the upper end of a compression spring 86, the lower end of which seats on a spring supporting element 87 here shown in the form of a centrally perforated disk, likewise movable longitudinally within tubular body 80. Spring supporting element 87 is engaged by the upper end of a screw member 88, screw-threaded within a lower head 89 screwed to a fixed position within the lower end of tubular body 80. A stop nut 90, secured to screw 88, as by means of pin 91, engages head 89 to limit the travel of screw 88 upwardly within body 80.

A tension rod 93 screwthreaded at its upper end into shaft supporting element 85 extends longitudinally through spring 86 and through an aperture 94 in spring supporting element 87, its lower end portion being received within a socket 95 in the end of screw 88. A rounded nut 96 screwed onto the lower end of rod 93 is tightly mounted in a predetermined position thereon and is loosely received inside socket 95, nut 96 being so located on rod 93 that there is a predetermined spacing distance between its upper end and the lower face of spring supporting element 87 when spring 86 is compressed (Fig. 6). Nut 96 may be secured in position as by means of a securing pin 96a. The end of the drum shaft thus rests on supporting element 85, and the downward pressure exerted thereby is transferred through spring 86, spring supporting element 87, screw 88 and head 89 to the body 80 of the hanger 76 suspended from the fixed frame.

When blades are installed in the machine, the screw 88 is backed down, allowing the spring 86 to move supporting element 87 into engagement with nut or head 96 on tension rod 93. The pressure exerted by the spring is thus assumed by tension rod 93, and screw 88 being sufficiently lowered, the spring assembly comprising spring 86, members 85 and 87, and rod 93, is lowered from supporting engagement with shaft end 83. Hanger 76 may then be swung out to the position

indicated in dotted lines in Fig. 2, enabling the blade loops to be passed on over the end of the upper drum. To permit the blades to be thus placed on the drum, however, the drum must be lowered somewhat, and this is accomplished by lowering lead screw 53 by means of crank 66. As this is done, stop nut 70 separates from bracket 57 and tension rod head 72 engages wall 50, after which drum shaft supporting member 45 lowers with lead screw 53. This lowering operation is carried on until the blades will go on easily over the drum.

When the spring supporting means are set up to the operating positions illustrated in Figs. 4 and 6, with the stop nuts 70 and 90 abutting their respective stops, the two supporting springs 51 and 86 are under a predetermined compression. This compression is predetermined in the factory at a value such as will assure proper tensioning of the blades by the drum 21, which is pressed in an upward direction by said springs, but such as will avoid-overstressing the blades and also the bearings and supporting provisions for the drums and drum shafts.

The predetermined compression of the springs is established as follows. For example, prior to assembly of the parts comprising hanger 76, the members 85 and 87, with the spring 86 therebetween, are forced toward one another, as in a vise, against the pressure of the spring, to a predetermined compression. This compression will of course vary with the design of the machine, but it will amount usually to several hundred pounds. While the spring 86 is accurately held under this compression which has been determined as proper, the nut 96 is then screwed onto tension rod 93 to a position such that there is a predetermined gap between its upper end and the adjacent face of member 87, which gap may be for example $\frac{1}{8}$ ". The compression is then relieved, allowing member 87 to engage nut 96. The spring assembly, then in the condition illustrated in Fig. 7, is then inserted within the tubular hanger body 80, head 89 is screwed in place, and screw 88 is advanced until member 87 is engaged and is moved upwardly until the $\frac{1}{8}$ " gap between the upper end of nut 96 and the adjacent face of member 87 is reestablished. Nut 90 is then screwed upwardly on screw 88 until it engages head 89, and is then pinned on screw 88 in that position. The device is then in the condition of Fig. 6, and the spring 86 is under the same compression as it was when in the vise. Now, whenever screw 88 is subsequently backed away, for the purpose of releasing the supporting pressure against the underside of shaft end 83, and is then reset, it is always screwed back up until nut 90 engages head 89. The predetermined compression of spring 86 is thereby accurately reestablished.

An exactly similar procedure is followed in establishing the compression of spring 51. Thus spring 51 is first assembled with member 45, member 52, tension rod 71 and lead screw 53. Members 45 and 52 are then clamped, as in a vise, and the spring 51 compressed to the predetermined compression value. Tension rod 71 is then adjusted until there is a predetermined gap between its head 72 and the wall 50. This gap will be the same as that provided between the member 87 and nut 96 of the other spring assembly, and may thus be $\frac{1}{8}$ ". The assembly is then removed from the vise, the spring 51 being allowed to expand to the limit imposed by the engagement of wall 50 with tension rod head 72. The

device is then assembled in the slicing machine; the blades are mounted on the drums, and the lead screw 53 is advanced or elevated until the head 72 of the tension rod 71 has become elevated above the wall 50 of drum shaft supporting member 45 (which is being held down by the blades) by the above mentioned predetermined spacing distance or gap. The nut 70 on lead screw 53 is then set up against bracket 57 and pinned fast to screw 53 in that position. The predetermined compression for spring 51 is thus established. And each time the lead screw is set up thereafter, it is always set up until stop nut 70 engages bracket 57, which operation assures maintenance or reestablishment of the predetermined compression of the spring.

By this means, both ends of the blade tensioning drum are spring-supported, and are under the same spring pressure. Moreover, there is assurance that no attendant will set the spring pressure up beyond the point preestablished in the factory. The blades are therefore always run at proper tension, and hence are not liable to stretching in service; moreover, over-strain on the drum mountings such as might result from over-tensioning the blades is prevented.

In order to complete the disclosure of an operative slicing machine, typical blade twisting guide means, loaf infeed means, and certain other adjuncts will be described, though these parts per se do not form a part of the present invention.

Along the blade courses between the drums, I provide spaced-apart blade twisting guide means, which can take various forms, one form being illustrated by the parallel, notched plates 110 and 111. These plates are spaced apart to form between them a slicing zone for the blades, and through this slicing zone the loaves or other articles to be sliced are fed. In this slicing zone the blades run in spaced parallel slicing planes, having been twisted into such planes by the guide grooves or notches in plates 110 and 111. Thus these plates 110 and 111, supported as later to be described, are provided with rows of aligned blade twisting guide slots 110a and 111a, respectively, adapted to receive the individual courses of the band blades and space them apart according to the slice thickness required. As will appear from the drawings, the downwardly and upwardly travelling courses of each band blade are received in adjacent guide slots of these plates 110 and 111, in such manner that each blade course makes a 90° twist between each guide plate and the drum from which, or onto which, that blade course is travelling.

Between guide plates 110 and 111, the blade courses are disposed in spaced parallel slicing planes. The two courses of each blade cross one another at an angle dependent upon the diameters of the drums and the distance between drum centers. In general, for reasons well understood in the art, it is desirable that this angle be as small as possible.

The lower guide plate 111 is shown provided with down-turned flanges or brackets 120, by which it is secured to a transversely extending flange member 121 which extends downwardly from the forward edge of a horizontal feed table 122, the latter, which is flush with the upper surface of guide plate 111, being supported in the machine frame in any suitable manner. In order to accommodate loaves of different sizes, it is desirable that upper guide plate 110 be vertically adjustable. In the illustrative construction here shown, plate 110 is mounted on the

forward portion of a loaf "hold-down" plate 124, which is in turn mounted, by means of brackets 125, on the lower end of a pair of vertically movable racks 126. The lower surfaces of plates 110 and 124 are flush, and together form an upper guide and hold-down plate for the loaves.

Racks 126 extend through guideways 126a formed in bearing mountings 127 secured to a transverse plate or bar 128. One end of this transverse bar 128 abuts and is welded to the upper portion 130a of a frame member or bracket 130 secured to and extending from the left hand angle member 15 as viewed in the aspect of Fig. 1. The other end of bar 128 is supported by a bracket 128a extending from the left-hand vertical angle member 15 as viewed in Fig. 3.

A horizontal, transversely extending shaft 132 is journaled in bearing mountings 121, and has gear teeth 133 meshing with racks 126 (Fig. 9). Rotation of this shaft 132 causes vertical movement travel of racks 126, and therefore adjustment of plates 120 and 124.

One end of shaft 132, here the end corresponding to channel member 14, is provided with a hand wheel 141, the shaft being shown as projecting through an aperture 142 in channel member 14 and hand wheel 141 being positioned outside said channel member, where it can be conveniently reached when the corresponding side door of the machine is opened. Mounted on shaft 132 between channel 14 and bracket 130 is a ratchet wheel 143, and an arm 144 pivotally mounted on the side of frame member 130a, as at 144a, is provided with a dog 145 adapted to engage between the teeth of ratchet wheel 143 to hold said ratchet wheel, and therefore shaft 132 on which the ratchet wheel is tightly mounted, against rotation. When it is desired to effect vertical adjustment of blade guide plate 110 and loaf hold-down plate 124, arm 144 is lifted to disengage dog 145 from ratchet wheel 143, permitting shaft 132 to be rotated by means of hand wheel 141. When the adjustment has been accomplished, arm 144 is lowered to reengage dog 145 with the ratchet wheel.

The loaf feeding means, for advancing the loaves through the slicing means, forms no part of the present invention, and any suitable or desired means for accomplishing this purpose may be provided. However, while any suitable loaf feeding means may be provided, I have, for the sake of completeness, indicated one simple illustrative type of loaf feeding means involving a reciprocating ram 160, operated through crank pin 161 and pivoted, slotted arm 162, and a gravity feed chute 165. It will be readily understood, without detailed explanation, how the loaves may travel down feed chute 165 to a position on feed table 122, forwardly of ram 160, and how said ram will engage and advance the loaf so deposited before it, forwardly along feed table 122, and finally between blade guide plates 110 and 111 and so through and clear of the blades. To prevent the succeeding loaf from lowering until the ram has been retracted, the ram is equipped with a rearwardly extending tail plate 166 which supports said succeeding loaf until the ram has been substantially fully retracted, as will be readily understood. This type of feeding mechanism is well known in the art and will require no further explanation.

Any suitable or conventional type of end guides for the loaves while being sliced may be provided. End guides for this purpose are indicated by numerals 168 and 169 in Fig. 2.

The loaves having been advanced through the slicing zone and clear of the blades, are received by any suitable means for conveying them from the slicer; I here typically and somewhat diagrammatically indicate for this purpose a downwardly inclined plate or table 170. It will be understood however that any suitable out-feed provisions may be employed, the details of which form no part of the present invention, and will therefore not require detailed illustration.

Preferably, for the purpose of backing up the blade courses at or near the slicing zone, and so that the blade courses will not be substantially deflected by the pressure of the loaves, I employ transversely extending blade backing-up rollers 172 and 173, the former being mounted somewhat above blade guide plate 110, so as to engage one set of blade courses, and the latter being mounted just below lower blade guide plate 111, so as to engage and back-up the other set of blade courses. These long blade backing-up rollers are rotatably mounted in any suitable manner on shafts 174 and 175, the latter being supported at one end as by means of mountings 176 and 177, respectively, projecting from frame members 15, and at the other end by brackets, such as 178 and 179, projecting from frame member 130.

I have now disclosed a multiple band blade slicing machine characterized by extreme simplicity of construction, assurance of proper tensioning pressure on all the blades, and characterized by positive assurance that neither the blades themselves nor the drum mountings will be over-stressed in service.

While I have now described and illustrated a present preferred embodiment of the invention, it will be understood this is for illustrative purposes only, and that various changes in design, structure and arrangement may be made without departing from the spirit and scope of the invention as defined in the appended claims.

I claim:

1. In a multiple band blade slicing machine embodying a stationary frame, a band blade drum against which run a multiplicity of endless band blades, a drum shaft on which said drum is revolvably mounted, the combination of mounting means for said drum shaft at one of its ends embodying a shaft supporting member tightly embracing the shaft end, means on said frame guiding said shaft supporting member for travel in a direction to increase the pressure exerted by the drum on said band blades, a spring supporting said shaft supporting member, and supporting means for said spring supported by said frame and adapted to be advanced with reference to said frame to a fixed operating position in which said spring exerts a predetermined pressure on said drum shaft supporting member, mounting means for the other end of said drum shaft embodying a mounting member connected with said frame and a shaft supporting member for said other end of said drum shaft associated with said mounting member, said mounting means being supported by said frame normally in a position with said shaft supporting member in supporting engagement with said other end of said drum shaft, but movable with reference to said frame in a manner to separate its shaft supporting member from the drum shaft end, said shaft supporting member being movable, when in a position of supporting engagement with the drum shaft end, relatively to said mounting member in a direction parallel to the

travel of the supporting member for the first mentioned end of the drum shaft, a spring associated with said mounting member adapted to support said shaft supporting member for said other end of said drum shaft, and supporting means for said spring mounted on said mounting member and movable thereon to and from a fixed operating position in which said spring exerts a predetermined pressure on the shaft supporting member which it supports.

2. In a multiple band blade slicing machine embodying a stationary frame, a band blade drum against which run a multiplicity of endless band blades, a drum shaft on which said drum is revolvably mounted, the combination of mounting means for said drum shaft at one of its ends embodying a shaft supporting member tightly embracing the shaft end, means on said frame guiding said shaft supporting member for travel in a direction to increase the pressure exerted by the drum on said band blades, a spring supporting said shaft supporting member, and supporting means for said spring supported by said frame and adapted to be advanced with reference to said frame to a fixed operating position in which said spring exerts a predetermined pressure on said drum shaft supporting member, a hanger for the support of the other end of the drum shaft pivotally connected with said frame, a shaft supporting member for said other end of said drum shaft associated with and carried by said hanger, said hanger being supported by said frame normally in a position with said shaft supporting member in supporting engagement with said other end of said drum shaft, but movable with reference to said frame in a manner to separate the shaft supporting member associated therewith from the drum shaft end, said shaft supporting member being movable, when in a position of supporting engagement with the drum shaft end, relatively to said hanger in a direction parallel to the travel of the supporting member for the first mentioned end of the drum shaft, a spring associated with said hanger adapted to support said shaft supporting member for said other end of said drum shaft, and supporting means for said spring mounted on said hanger and movable thereon to and from a fixed operating position in which said spring exerts a predetermined pressure on the shaft supporting member which it supports.

3. In a multiple band blade slicing machine embodying a stationary frame, a band blade drum against which run a multiplicity of endless band blades, a drum shaft on which said drum is revolvably mounted, mounting means for one end of said drum shaft embodying a hanger pivotally connected with said stationary frame and a shaft supporting element for said shaft end associated with said hanger for movement toward and from the pivot of said hanger, said hanger being supported by said frame normally in a position with said shaft supporting element in engagement with said drum shaft end, but movable with reference to said frame in a manner to separate said shaft supporting element from the drum shaft end, a spring associated with said hanger supporting said shaft supporting element, and supporting means for said spring mounted on said hanger and movable thereon to and from a predetermined operating position in which the spring exerts a predetermined pressure on the drum shaft end.

4. In a multiple band blade slicing machine embodying a stationary frame, a band blade

drum against which run a multiplicity of endless band blades, a drum shaft on which said drum is mounted, and mounting means for said drum shaft at each of its ends, each of which comprises the combination of a pair of spaced members and a compression spring acting therebetween, a tension member extending between and limiting the separation of said spaced members to a given spacing distance, one of said members being adapted to support the corresponding end of the drum shaft, and means acting between the other of said spaced members and said fixed frame and movable against the opposition of said spring to a predetermined position to reduce the said spacing distance between said members by a predetermined amount, whereby a predetermined supporting pressure is exerted by said spring against said drum shaft end.

5. In a multiple band blade slicing machine embodying a frame, a band blade drum against which run a multiplicity of endless band blades, and a drum shaft for said drum, supporting means for an end of said shaft embodying the combination of a pair of spaced members and a compression spring acting therebetween, means associated with said pair of spaced members and adapted to act in tension against said spring to limit the separation of said members to a predetermined spacing distance, one of said members being adapted to support said end of said drum shaft, and means acting between the other of said spaced members and said frame and movable against the opposition of said spring to a predetermined position to reduce the spacing distance between said members by a prede-

termined amount, whereby a predetermined supporting pressure is exerted by said spring against said drum shaft end.

6. In a multiple band blade slicing machine embodying a band blade drum against which run a multiplicity of endless band blades, a drum shaft on which said drum is mounted, and mounting means for said drum shaft at each of its ends, each of which embodies a guide for guiding the drum shaft end for movement in a direction to tension and de-tension the blades, a compression spring supporting said drum shaft end and urging it to move in a direction to tension the blades, and adjusting and supporting means for said spring movable to and retractable from a predetermined pressure limiting operating position in which said spring resiliently supports said drum shaft end with a predetermined limited blade tensioning pressure, said spring adjusting and supporting means including an axially adjustable screw, a stop shoulder on said screw, and a fixed stop engageable by said stop shoulder on said screw when said screw has been set up to said predetermined pressure limiting operating position, the stop shoulders on the screws of the two drum shaft mounting means always being in engagement with their respective fixed stops when the slicing machine is in normal operating condition, so as to definitely establish the blade tensioning pressure exerted on the drum shaft ends exactly at said predetermined limited pressure and thereby set the tension of the blades at a corresponding fixed predetermined tension.
